[57] CLAIM

The ornamental design for a stuffed animal, as shown and described.

DESCRIPTION

FIG. 1 is a front elevational view of a stuffed animal showing my new design;

FIG 2 is a rear elevational view thereof;

FIG 3 is a right side elevational view thereof;

FIG. 4 is a top plan view thereof; and

FIG. 5 is a bottom plan view thereof.

FIG. 1

FIG. 3

FIG. 4

FIG. 5
